UNITED STATES PATENT OFFICE

2,357,601

RAZOR BLADE HOLDER

Eugene M. Perkins, Boston, Mass.

Application October 14, 1943, Serial No. 506,194

11 Claims. (Cl. 30—53)

This invention relates to safety razor blade honing and stropping and is concerned with a novel combination of honing and stropping blade holder and blade, the latter being of the type provided at its back or thickened rear portion with a socket to receive a stud on a blade carrier. The invention aims to provide a novel and improved substitute for the usual and well-known Rolls honing and stropping mechanism, and whose characteristics shall be such that honing and stropping can be carried out with standard hones and strops of the character usually employed for the old-fashioned, or "straight" razor, so-called, with all the advantages flowing from the use of ordinary hones and strops, thereby obviating certain disadvantages inherent in the Rolls mechanism.

The invention will best be understood by reference to the following description when taken in connection with the accompanying drawing of several embodiments thereof, while its scope will be pointed out more particularly in the appended claims.

In the drawing:

Fig. 1 is a plan of a razor blade and a honing and stropping holder embodying the invention;

Fig. 2 is a side elevation of the same;

Fig. 3 is a plan of a portion of the holder by itself;

Fig. 4 is a cross-sectional view on line 4—4 of Fig. 1;

Fig. 5 is a sectional view on line 5—5 of Fig. 2, showing the holder and the blade locked together;

Fig. 6 is a sectional view similar to Fig. 5, but showing the holder unlocked from the blade in readiness for detachment therefrom;

Fig. 7 is a sectional view on line 7—7 of Fig. 2; Fig. 8 is a sectional view on line 8—8 of Fig. 2, showing the holder and blade locked together;

Fig. 9 is a sectional view similar to Fig. 8, showing the holder unlocked from a blade in readiness for detachment therefrom; and

Figs. 10 to 18, inclusive, are views illustrating several modifications or variations of the invention.

Referring to the drawing and having reference at first more particularly to Figs. 1 and 2, there is shown a Rolls type blade 23 equipped with a usual guard 25. The blade has the usual concave surfaces 27 meeting in a cutting edge 29 and diverging rearwardly to form a thickened back 31 having a rear surface 33. The blade is provided with the usual socket 35 characteristic of the Rolls type blade and comprising two conical portions 37 and 39, one (a truncated cone)

larger than the other, with a shoulder 41 between them. Leading into the larger, truncated conical portion 39 is an entrance opening or aperture 43 which (see Fig. 1) is elongated lengthwise of the blade, and (see Figs. 5 and 6) is separated from the conical portion 39 by shoulders 45 which overhang the latter.

The described socket receives a stud 47 having conical portions 49 and 51 corresponding to the conical portions of the socket except that the larger, truncated conical portion 51 (see Figs. 8 and 9) is slabbed to form flat faces 52 and thus is elongated to coincide with and to enter the elongated entrance opening or aperture 43 when in the position shown in Figs. 6 and 9. But when turned through an angle of 90° into the position shown in Figs. 5 and 8, the stud is securely interlocked with the blade by virtue of the fact that the stud has, in effect, two lips 53 (see Fig. 3) which normally underlie the shoulders 45, respectively.

The described stud is suitably formed on or secured to a handle 55 having a shank 57 and a grasping portion 59, each of novel construction, the handle normally being disposed lengthwise of the blade 23. To retain the handle in this position, the handle and the blade, in accordance with my invention, may be constructed in various ways to interengage with each other, thereby to accomplish the normal retention of the handle in the position in which the stud 47 interlocks with the blade 23. One example is illustrated in Figs. 1, 2, 3 and 7, while others are illustrated in Figs. 10 to 18, inclusive.

The example illustrated in Figs. 1, 2, 3, and 7 will now be described, reference being had at first to Fig. 7. In this example, the back 31 of the blade is provided with a depression or depressions 61, either short depressions as shown in Fig. 1, or long depressions 61A, separated only by the aperture 43, as in Fig. 10, and cylindric as in Fig. 7, or V-shaped as at 61B in Fig. 11, or there may be hemispheric depressions as at 61C in Fig. 12. Alternatively, the blade may be provided with projections such as ribs 63, cylindric, as in Fig. 13, or V-shaped, or hemispheric as at 63A in Fig. 14. In the latter case, the hemispheres may be formed as integral parts of the blade or as steel balls inserted into the blade.

In any case, the shank 57 of the handle is appropriately constructed for cooperation with these depressions or projections, though in each case the shank preferably has the characteristic of being elastic and thereby constituting a spring 55 detent interengagable with the indentations or

projections on the blade. One way of making the shank sufficiently elastic for the purpose is to weaken the same as by a depression 65 at the top, and also, if desired a second depression 67 at the bottom, so that the shank will be locally elastic, though possibly these might be dispensed with if the shank is sufficiently slim to be adequately elastic. In the example shown in Figs. 1, 2, 3 and 7, the shank otherwise is cylindric to correspond with the cylindric depression or depressions 61, or 61A, or to enter the V-shaped depressions 61B, or in the case of the latter, the shank may be correspondingly V-shaped in cross-section. If, however, hemispheric depressions 61C are employed, the shank will have a projection 69 (see Fig. 15) either hemispheric or conical.

On the other hand, if the blade is provided with projections such as 63 or 63A, the shank will be provided with a cylindric or a V-shaped groove 71 (see Fig. 16) or a hemispheric depression 73 or a conical depression 75 (see Figs. 17 and 18) to receive the projections 63A.

In any case, the interengaging depressions and projections may be at only one end of the blade, or at both ends. The advantage of having them at both ends is that the interengagement can take place at either end of the blade, as a matter of convenience. In either case, to enable the shank to ride up on the blade, prior to the interengagement, the blade is provided with a bevelled surface or surfaces 77, in this example four such surfaces, so that the shank can approach the blade from either direction and will ride up on a bevelled surface and snap into place by reason of its resiliency. When in place, the handle is securely interlocked with the blade because in this position of the handle the lips 53 of the stud 47 are engaged with the shoulders 45 and because the handle remains in position lengthwise of the blade. To remove the handle from the blade, the handle is swung through an angle of 90° (compare Figs. 8 and 9) and the lips 53 of the stud 47 now register with the elongated slot 43 and can pass through the latter to permit the stud to be withdrawn lengthwise of its axis of rotation. A blade holder for shaving purposes can then be substituted for the described honing and stropping holder.

To facilitate the turning of the blade holder about the longitudinal axis of the handle in honing or stropping, the handle is provided with a knurled portion 79 to be grasped between the thumb and the index finger, while the remaining portion 81 preferably is smooth to turn readily in the remaining fingers. In the present example, this turning action is further facilitated by making the portion 81 as a sleeve turning about a shaft 83. The portion 79 to be grasped between the thumb and forefinger may be provided with two or more flat faces 85 as an aid in controlling the turning of the blade holder in honing or stropping. To prevent the thumb and forefinger from slipping toward the blade, the handle may be provided with a flange 87 between the grasping portion and the shank 37.

Having thus described these several embodiments or variations of the invention, what I claim and desire by Letters Patent to secure is:

1. The combination of a razor blade having a thickened back provided with a socket, and a honing and stropping holder having a handle extending lengthwise of and beyond one end of said blade, said holder having a stud transverse to said handle, rotatable within said socket and hav-

ing laterally projecting means normally interlocked laterally with said socket.

2. The combination of a razor blade having a thickened back provided with a socket, and a honing and stropping holder having a handle extending lengthwise of and beyond one end of said blade, said holder having a stud transverse to said handle and having laterally projecting means normally rotatably interlocked laterally with said socket to turn about an axis transverse to said handle, said blade and said holder having cooperative means normally to resist turning of said stud and said handle about the axis of said stud.

15 3. The combination of a razor blade having a thickened back provided with a socket, and a honing and stropping holder having a handle extending lengthwise of and beyond one end of said blade, said holder having a stud transverse to said handle and having laterally projecting means normally interlocked laterally with said socket, said blade and said holder being provided, one with a depression and the other with a projection which normally is received in said depression and means which causes said projection to leave said depression when said handle and said stud are turned about the axis of rotation of said stud.

20 4. The combination of a razor blade and a holder therefor, said blade being provided with a socket transverse to its cutting edge and provided with a lateral recess, and said holder being generally L-shaped and comprising an attaching portion rotatably received in said socket, and provided with a lateral projection received in said recess, and a handle extending from said socket along the back of said blade and beyond one end thereof.

25 5. The combination of a razor blade and a holder therefor, said blade being provided with a socket transverse to its cutting edge and provided with a lateral recess, and said holder being generally L-shaped and comprising an attaching portion rotatably received in said socket, and provided with a lateral projection received in said recess, and a handle extending from said socket along the back of said blade and beyond one end thereof, said handle and said blade being normally interlocked with each other between said socket and one end of said blade to resist turning of said attaching portion in said socket.

30 6. The combination of a razor blade and a holder therefor, said blade being provided with a socket transverse to its cutting edge and provided with a lateral recess, and said holder being generally L-shaped and comprising an attaching portion rotatably received in said socket, and provided with a lateral projection received in said recess, and a handle extending from said socket along the back of said blade and beyond one end thereof, said handle and said blade being normally interlocked with each other between said socket and one end of said blade to resist turning of said attaching portion in said socket, said handle having resilient means arranged to yield and to permit such turning.

35 7. The combination of a razor blade and a holder therefor, said blade being provided with a socket transverse to its cutting edge, and said holder being generally L-shaped and comprising an attaching portion received in said socket, said socket and said attaching portion having laterally interengaging means, and a handle extending from said socket along the back of said blade and beyond one end thereof, said handle and said blade being normally interlocked with each other

between said socket and one end of said blade to resist turning of said attaching portion in said socket, said handle having resilient means arranged to yield and to permit such turning, and said blade being provided with a bevelled surface to facilitate restoration of said handle to its normal position.

8. The combination of a razor blade and a holder therefor, said blade being provided with a socket transverse to its cutting edge, and said holder being generally L-shaped and comprising an attaching portion received in said socket, said socket and said attaching portion having laterally interengaging means, and a handle extending from said socket along the back of said blade and beyond one end thereof, said handle and said blade being normally interlocked with each other between said socket and one end of said blade to resist turning of said attaching portion in said socket, said handle having resilient means arranged to yield and to permit such turning, and said blade being provided with a bevelled surface to facilitate restoration of said handle to its normal position, and said blade being provided with a bevelled surface to cause said resilient means to yield while said handle is being restored to its normal position.

9. The combination of a razor blade and a holder therefor, said blade being provided with a

socket transverse to its cutting edge, and said holder being generally L-shaped and comprising an attaching portion rotatable in said socket, said socket and said attaching portion having laterally interengaging means, about an axis transverse to the cutting edge of said blade, and a handle having a shank leading from said attaching portion lengthwise of and along the back of said blade, and a grasping portion beyond said shank, said shank being elastic, and said blade and said shank being cooperatively arranged to utilize the elasticity of said shank normally to resist turning of said holder about said axis.

10. A razor blade holder comprising a blade attaching stud having laterally projecting means for interlocking laterally with a blade, and a handle transverse to said stud and having a grasping portion and an elastic blade-engaging portion between said grasping portion and said

20 stud.

11. A razor blade holder comprising a blade-attaching stud having laterally projecting means for interlocking laterally with a blade, and a handle transverse to said stud and having a 25 grasping portion, a blade-engaging portion which is elastic between said grasping portion and said stud in a plane containing the axis of rotation of said stud.

EUGENE M. PERKINS.
